UNITED STATES PATENT OFFICE.

BARTON H. JENKS, OF BRIDESBURG, PENNSYLVANIA.

IMPROVED PROCESS OF SEASONING WOOD.

Specification forming part of Letters Patent No. 58,425, dated October 2, 1863.

To all whom it may concern:

Be it known that I, BARTON H. JENKS, of Bridesburg, in the county of Philadelphia and State of Pennsylvania, have invented a new and Improved Process of Seasoning Woods; and I do hereby declare that the following is a full, clear, and exact description thereof, reference being had to the accompanying drawings, making a part of this specification, in which—

Figure 1 is a side view of an exhausting-engine applied to a vessel for containing wood to be seasoned. Fig. 2 is an end view of the receiver.

Similar letters of reference indicate corresponding parts in both figures.

The object of my invention is to obtain a more rapid drying or seasoning of timber by inclosing the same when in a wet or green state within an air-tight vessel, and exhausting the air from it, thereby opening the spiracles or capillary vessels of the wood and evaporating the juices therein.

The usual method of seasoning timber is to expose it to the action of dry air for a considerable space of time, according to the size of the logs or planks. This plan, if continued long enough, will effectually dry the timber without injury to it; but it is objectionable on account of the long time required before the timber is fit for use.

Other plans for the more rapid seasoning of timber have been tried, such as kiln-drying it, steaming it, and subjecting it to currents of highly-heated air; but it has been found that the rapid drying by heat contracts the pores of the wood at and near the surface, and prevents the interior moisture from escaping.

To enable others skilled in the art to understand my invention, I will describe one practical mode of conducting the process.

In the accompanying drawings, A represents a strong cylindrical vessel, which is suitably supported in a horizontal position, and provided with a movable head, B, that should fit air-tight in its place. A clamp, C, and screw, C', or other suitable means should be employed for securing the head B upon the cylinder A,

and admitting of the ready removal of this head at pleasure.

Instead of a cylindrical vessel, A, a cubical or other shaped vessel may be used; but I prefer the cylindrical form, on account of its superior strength.

One or more pipes, a, lead off from the vessel A to an exhausting-engine, D, for the purpose of exhausting air from the vessel A when desired. The air pump or engine D may be made of the well-known form.

If desirable, a steam-jacket may surround the cylinder A, or heat may be applied to this cylinder in any other suitable manner, if it is found desirable, for the purpose of softening the gummy matter in the pores of the wood.

If the cylinder A be made very large and the timber to be seasoned be very heavy, a carriage, G, may be employed for supporting the timber and allowing it to be readily introduced into and removed from the cylinder.

The process of seasoning is conducted by first introducing the green or wet timber into the cylinder A, and inclosing it air-tight therein. The air is then exhausted to the utmost from the cylinder, and the timber allowed to remain in the vacuum for several hours, after which the timber is removed and stacked for use.

If heat be employed for softening the glutinous or resinous matters in the wood, it is applied either before exhausting the air from it or during this exhausting process.

The objection which applies to wood which is heated for seasoning it, as above mentioned, will not apply in the process as conducted by me, as the pores of the wood will be opened, and the water forcibly ejected therefrom, by the vacuum, and there will not be an opportunity for the pores of the wood to contract and prevent the moisture from escaping.

The process of exhaustion should be carried on until the air comes out of the cylinder containing the timber perfectly dry. The stop-cock b can then be closed, and the timber allowed to remain in the vacuum for a short time, when the air-pump may again be worked—after opening cock b—for exhausting any moisture

which may have been drawn out of the wood by the vacuum.

If desirable, the wood may be subjected to a dry heat after its removal from the cylinder or receiver, for the purpose of preventing condensation of moisture upon the surface and in the pores of the wood.

Having described my invention, what I claim

as new, and desire to secure by Letters Patent, is—

The process, substantially as herein described, of seasoning or drying woods.

BARTON H. JENKS.
